UNITED STATES PATENT OFFICE.

ALBERT E. MOORHEAD, OF UKIAH, CALIFORNIA.

ROTARY VALVE.

1,218,296.

Specification of Letters Patent. Patented Mar. 6, 1917.

Application filed July 24, 1916. Serial No. 110,919.

To all whom it may concern:

Be it known that I, ALBERT E. MOORHEAD, a citizen of the United States, residing at Ukiah, in the county of Mendocino 5 and State of California, have invented new and useful Improvements in Rotary Valves, of which the following is a specification.

The present invention relates to improvements in rotary valves for combustion engines, and the object of the invention is to provide a rotary valve which will permit of high speed, which will be comparatively noiseless, which will eliminate undue frictional resistance, the port of which will not leak, which can expand freely, in which the surface heat will be reduced, which will be independently flexible, and in which a superior oiling system can be used.

In the accompanying drawings, Figure 1 is a plan view of an internal combustion engine equipped with my improved valve, the cover being removed and some of the valves being shown in horizontal section; Fig. 2 is a broken bottom plan view of said cover; Fig. 3 is a broken longitudinal view of the engine; Fig. 4 is a broken cross sectional view through the centers of the valves thereof; Fig. 5 is a similar view through valve couplings; Fig. 6 is a view similar to Fig. 3 showing modifications of the invention; Fig. 7 is an end view of a modified form of valve; Fig. 8 is a longitudinal section of the same; Fig. 9 is a transverse section of the same; Fig. 10 is a side view of an end section of a valve; Fig. 11 is a face view thereof; Fig. 12 is a detail side view of a support for a handle; Fig. 13 is an end view of the same; Fig. 14 is an end view of the same showing the handle in a different position from that in Fig. 13.

Referring to the drawing, 1 indicates a casting comprising the walls of cylinders 2. 3 indicates a second casting comprising the tops 4 of said cylinders, walls 5 of water jackets and the under sides 6 of valve casings. Copper gaskets 10 are interposed between the adjacent portions of the castings 1, 2 and 3. 7 indicates an upper casting comprising walls 8 of water jackets and upper sides 9 of valve casings. Said valve casings are spherical in form and in each valve casing is contained a valve constructed in accordance with my invention.

The valve contains three main parts, a central part 11 and two terminal parts 12. The central part 11 is approximately in the

form of a sphere from which two segments have been cut off along planes parallel with each other. The terminal parts 12 are approximately in the form of said segments; 60 each segment having a cylindrical extension 13 from its center, said cylindrical extension terminating in an enlarged globular head 14. The adjacent globular heads of two adjacent valves are contained in the 65 ends of a tube 16, having in its ends open-ended longitudinal slots 17 through which extend pins 18, which are driven diametrically through the globular heads 14 in the respective ends. The pins at opposite ends 70 of the tube are arranged at right angles with each other, and hence, if a rotary motion, imparted thereto, be communicated from either head to the other head, each head will still be capable of turning freely with reference to the other head in a plane through the axis of the tube.

This rotary motion is communicated by means of keys 19 longitudinally movable in grooves 21, 22, formed in the opposing faces 80 of the central and terminal portions of the valve. It will readily be seen that by means of these keys, any rotary motion imparted to a globular head will be communicated to the main or central portion of the valve, while 85 at the same time the axes of said main or central portion need not be in exact alignment with each other.

Each terminal portion and the extension therefrom are formed with a deep axial recess 23 in which is contained a coiled spring 24 compressed between the bottom of the recess and the key 19, and therefore pressing said key against the bottom of the groove in the central portion of the valve and pressing 90 the segmental part of the terminal portion of the valve against the spherical valve casting, thus making a tight joint at the entrance to said valve casting.

The head of each cylinder communicates 100 by an axial passage 26 with a transverse passage 27 leading at its ends to two valve chambers and with each end of the transverse passage 27 can communicate a port 28 formed transversely in the central part 11 of 105 the valve in said casing and extending entirely therethrough, one of said valves serving as the inlet valve and the other as the exhaust valve. The ports 28 through the respective valves communicate on the outside 110 with transversely extending ports 29, 30, respectively in the valve casing, the port 29

on one side leading to the intake manifold and the port 30 on the other side to the exhaust manifold.

I have herein shown the valves as arranged in a four-cylinder engine, the valves being turned by a shaft 31 operated by the crank shaft and carrying a screw gear 32 meshing with a screw gear 33 which meshes with a companion screw gear 34, said screw gears 33 and 34 being mounted on shafts 35, 36, rotating in bearings 37, 38, and having on their ends globular heads operatively connected with the valves in like manner as are the globular heads of the extensions from the valves. It will thus be seen that the two valves for each cylinder rotate in opposite directions, and each valve makes one-half of a revolution with two complete reciprocations of the piston in the cylinder, so that each end of the port 28 in each valve is alternately the inlet end and the outlet end.

Fig. 4 of the drawings shows companion valves in the position in which the intake valve is fully opened, and the piston is about in the middle of its downward stroke drawing in gas from the carburetor. The compression of the gas and the explosion period both take place before the exhaust port of the other valve is open to the exhaust outlet.

For cooling the exhaust valve, I may provide an adjustable valve 41 for admitting water from the water jacket to the interior of said valve. Said valve 41 fits in a conical seat 42 in the exhaust valve casing, and has a stem 43 extending through a threaded plug 44 and surrounded by a spring 45 compressed between said bearing and the head of the valve 41. The outer end of said stem is threaded, as shown at 46, and is screwed into a transversely extending handle 47. A set screw 48 is provided to secure the handle wherever adjusted. A sheet metal seat 49 is provided between the handle and the head of the threaded plug 44, said seat having its sides bent upwardly, as shown at 51, the edges of said sides being concave, as shown at 52, to receive said handle. To vary the opening 50 through which the water escapes from the water jacket into the interior of the exhaust valve, the handle is screwed around the threaded stem to the proper distance and is then caused to rest in the concave portions 55 of the sides of the seat. A small amount of water is then admitted to the interior of the exhaust valve with each half revolution of said valve, and, when the exhaust valve is open to the cylinder and the exhaust port 30, said water is immediately thrown out through said port 30.

In the modification of the invention shown in Figs. 8 and 9, a rectangular metal casing, the space between which and the outer wall 65 of the valve is filled with asbestos or other

insulating material, forms the wall of the port 28.

The chambers 53 extending longitudinally between adjacent globular valve casings, and containing the extensions 18 and heads 14 70 and tubes 16 surrounding the same, is filled with oil, and said extensions are formed with small openings 54 leading from said chambers to the recesses 23, so that oil penetrates also the spaces between the central 75 and terminal portions of the valves.

It will be seen that the central portions of the valves need not fit tightly on both sides against the valve casing, provided that both sides, near the ends of the port 28, are of the same diameter as the valve casing, for the pressure of the gases in the cylinders will press their outlet sides against the corresponding portions of the valve casing, and thus make a tight joint at their outlet 85 sides.

It will be seen that, in my improved valve, frictional resistance has been reduced to the smallest possible degree, since the valve is spherical and its central section is full 90 floating. Taking the frictional resistance of a disk as 100, that of a round shaft as 50, and that of a sphere as 30, when two motions at right angles to each other are added to the motion of the spherical valve, as 95 in the present case, the frictional resistance will be 50% less than that of its original single motion. This then results in a frictional resistance of about 15%, which is believed to be the least possible.

The ports have no more chance of leaking than a puppet valve or any other type of valve, due to the fact that they are spherical and always closing on a perfect and self-ground seat. The leakage common in mechanical valves across and under the near side of the valve caused by the pressure, either from within or from without, is eliminated in this case by the provision of spherical end walls and by the fact that the 105 spherical valve is divided into three parts so separated that the ends, by a slight spring pressure, are forced to the spherical end walls of the casing, and so prevent the leakage which has been so common in all other mechanical valves.

It is obvious from the construction that the valve is free to expand in all directions.

Since the inner and outer surfaces of the valve may be packed with asbestos or any 120 other non-conductor, the heat of the wearing surfaces is greatly reduced.

Since each valve is independently flexible, warping or strains due to reheating cannot be effective in this full floating valve mechanism.

Since the oiling is accomplished by providing oil pits at the ends of each valve, the valve stems and the flexible universal joints are operating within a bath of oil.

- By the provision of an oil hole leading to the space between the full floating port member and the expansion end members, oil is thrown from this space by centrifugal force to the outer walls around the central port member, and is regulated by a pressure sufficient to maintain a film of oil, while preventing flooding. And in view of the fact that the frictional resistance has been reduced to the least possible, the oiling becomes of much less consideration. As the frictional resistance decreases, the amount of oil naturally decreases in direct proportion.
- Practical experience proves that all rotary movements cause even wear, regardless of whether or not the pressure may be exerted at one or more designated points throughout its cycle of rotation. This is illustrated by the case of a cross head pin and a crank pin of a reciprocating engine. The cross head pin, due to its reciprocating motion, wears unevenly directly in line with the pressures exerted, and it therefore becomes necessary in the course of time to file the pin at the top and bottom, or at right angles to the pressure exerted, as this pin eventually becomes oblong. The crank pin, due to its rotary motion, maintains throughout the life of the engine its rounded condition, regardless of the fact that the pressures exerted are not uniform.
- Undoubtedly a sphere rotating within a casing, and with a slight oscillation, will maintain its true spherical shape and be self-grinding throughout the life of any gas engine in which it is used, as, by reason of their larger diameters and higher speeds and greater heat in the piston, the piston and crank shafts are more subject to short life than the valve of small diameter and a speed slower than that of the crank shaft in the proportion of 1 to 4.
- I claim:—
1. In combination with a globular casing, a rotary valve comprising a central section having a port therethrough, and a terminal section operatively connected to rotate together, the central section being approximately in the form of a sphere from which a segment has been cut off at opposite sides and the terminal section being in the form of said segment, and means for pressing the terminal section from the central section.
  2. In combination with a globular casing, a rotary valve comprising a central section having a port therethrough, and a terminal section operatively connected to rotate together, the central section being approximately in the form of a sphere from which a segment has been cut off at opposite sides and the terminal section being in the form of said segment, and compressed springs interposed between the central and terminal sections for pressing the terminal section from the central section.
  3. In combination with a globular casing, a rotary valve comprising a central section having a port therethrough, and a terminal section operatively connected to rotate together, the central section being approximately in the form of a sphere from which a segment has been cut off at opposite sides and the terminal section being in the form of said segment, means for pressing the terminal section from the central section, the terminal section having an extension with a rounded head, a loose joint for connecting said head with a rotary device to impart rotary motion to the terminal section, and means whereby the rotation of the terminal section rotates the main section.
  4. In combination with a globular casing, a rotary valve comprising a central section having a port therethrough, and a terminal section operatively connected to rotate together, the central section being approximately in the form of a sphere from which a segment has been cut off at opposite sides and the terminal section being in the form of said segment, means for pressing the terminal section from the central section, the terminal section having an extension with a rounded head, a loose joint for connecting said head with a rotary device to impart rotary motion to the terminal section, the faces of said terminal and the main section having registering grooves, and a key in said grooves.
  5. In combination with a globular casing, a rotary valve comprising a central section having a port therethrough, and a terminal section operatively connected to rotate together, the central section being approximately in the form of a sphere from which a segment has been cut off at opposite sides and the terminal section being in the form of said segment, means for pressing the terminal section from the central section, the terminal section having an extension with a rounded head, a loose joint for connecting said head with a rotary device to impart rotary motion to the terminal section, the faces of said terminal and the main section having registering grooves, and a key in said grooves, said terminal sections having a recess opening from its face opposite to the central section, a compressed spring in said recess, the terminal and main sections having registering grooves, a key in said grooves, said spring pressing against said key.
  6. In combination with a globular casing, a rotary valve comprising a central section having a port therethrough, and a terminal section operatively connected to rotate together, the central section being approximately in the form of a sphere from which a segment has been cut off at opposite sides

and the terminal section being in the form of said segment, means for pressing the terminal section from the central section, the terminal section having an extension 5 with a rounded head, a loose joint for connecting said head with a rotary device to impart rotary motion to the terminal section, the faces of said terminal and the main

section having registering grooves, and a key in said grooves, said terminal sections having an extension with a rounded head, a tube around said head having slots opening in its end adjacent to said central section, and a pin through said rounded head having its ends in said slots.

ALBERT E. MOORHEAD.
